UNITED STATES PATENT OFFICE

101,405

DESIGN FOR AN AUTOMOBILE

Max S. Schneider, Chicago, Ill.

Application May 25, 1936, Serial No. 62,817

Term of patent 7 years

To all whom it may concern:

Be it known that I, Max S. Schneider, a citizen of the United States, residing at Chicago, in the county of Cook and State of Illinois, have invented a new, original, and ornamental Design for an Automobile, of which the following is a specification, reference being had to the accompanying drawing, forming a part thereof in which

Fig. 1 is a perspective view of an automobile showing my new design; and

Fig. 2 is an enlarged sectional view on the line 2—2 of Fig. 1.

The portion illustrated in solid black lines is the dominant feature of my design.

I claim:

The ornamental design for an automobile as shown and described.

MAX S. SCHNEIDER.
